APPARATUS FOR CLEANING LUBRICANT RECEPTACLES AND THE LIKE

George E. Saussure, Pittsburgh, Pa., assignor to
 Internal Motor Cleaner Company, Pittsburgh,
 Pa., a corporation of Pennsylvania

Application March 22, 1938, Serial No. 197,428

16 Claims. (Cl. 184—1.5)

This invention relates to improvements in apparatus for cleaning lubricant receptacles and the like, and has particular application to the art of cleansing or flushing the crank cases of internal combustion engines, the transmission and differential cases of motor vehicles, and other similar receptacles.

The general principle employed is that of supplying a cleansing or flushing oil to the previously drained lubricant receptacle in order to remove waste and foreign matter therefrom, and includes the refining or reclaiming of the flushing oil for re-use.

It is a prime object of my invention to provide a cleaning apparatus capable of supplying, recirculating, removing and refining or reclaiming a body of flushing fluid or oil for cleansing or flushing a lubricant receptacle, operable through a system of conduits and a master control for successively performing these and other steps in a selective cycle of operation.

Another object hereof is to heat the flushing oil in relation to and during the circulation thereof in such a manner that only that portion of the oil utilized is heated, thereby dispensing with the losses incurred in heating an entire supply of oil as when heating in a reservoir or the like.

I also contemplate the recirculation and re-heating of an initially supplied quantity of flushing oil for proper loosening and removal of the foreign material from the lubricant receptacle.

A further object is to provide for increasing the capacity of the apparatus to enable the same to be readily usable for cleansing large receptacles, as for example, the crank cases of Diesel engines, by simple connection with additional containers of oil and without in any way affecting the normal operation of the device.

Still further objects are: to provide a centralized control for rapid and efficient adjustment of the apparatus in the various steps necessary to a complete and thorough cleansing cycle; to provide for the positive segregation and removal of the foreign materials entrained in the flushing oil, including the heating of the dirty oil prior to filtration thereof; and to provide an apparatus which will be efficient and economical in construction and operation, and which will have sufficient capacity for continued service over a long period of time.

Additional objects and advantages will become apparent from the following description, taken in connection with the accompanying drawings, wherein:

Fig. 1 is a front elevational view, partly in sec-

tion, illustrating a preferred embodiment of my invention;

Fig. 2 is a view similar to Fig. 1 showing a modified form of my invention;

Fig. 3 is a rear elevational view of the control device of Fig. 1, showing the conduit connections therewith;

Fig. 4 is an enlarged vertical sectional view of the control device or valve of the apparatus;

Fig. 5 is a longitudinal sectional view taken through one of the circulation heaters;

Fig. 6 is a similar view taken at right angles to the view of Fig. 5;

Fig. 7 is an enlarged cross-section taken on the line VII—VII of Fig. 5; and

Fig. 8 is a wiring diagram of the heating system and the actuation thereof by the control device.

In the drawings, the apparatus has been illustrated in operative relation with some of the elements spaced apart more than may be required in actual practice, for the sake of clarity in following the fluid circulation therethrough, it being understood that it is intended that the apparatus may be suitably mounted and enclosed within a cabinet or housing indicated by the dotted line 9.

The apparatus may be best described by its relation to and inter-connection with a central control device or valve 10. Said control device may be of any suitable construction embodying means for establishing communicating circulation between a fluid pump 11 and a plurality of utilizing means. Said device acts as a fluid distributor for separately connecting the pump in circulation with those elements and conduits of the apparatus through which the flushing oil is to be circulated, according to the method of cleansing or flushing practiced.

I prefer to employ and have therefore illustrated herein a control device or valve of my invention, the construction and form of which is covered in a separate application of even date, bearing Serial No. 197,429, now Patent No. 2,240,227, issued April 29, 1941, to which reference may be had for a more detailed description of the said device.

Generally, the device 10 as preferred, includes a pair of stationary members 12 and 13, between 50 and in contact with which a plate 14 is rotatably mounted by a shaft 15 journaled in the stationary members. (See Fig. 4.) The pressure conduit 16 and the suction conduit 17 from the pump 11 connect with separate inner annular distributing channels 18 and 19 respectively, said chan-

nels each having a port or passage 20 and 21 respectively, extending through the rotatable plate 14.

Ports 20 and 21 are diametrically disposed for alinement with diametrically disposed pairs of ports or rearward discharge openings 22 in the member 13, whereby through rotation of the plate 14 by the indicator handle 23 on shaft 15 in the front of the device, the pump 11 may be connected in fluid circulation with any of a series of the diametric pairs of ports. Suitable sealing means are provided for preventing leakage between the stationary and rotatable members of the device, and means, such as a rear spring 24, is provided for maintaining the members in operative assembly.

Referring to the embodiment of Fig. 1, 25 and 26 designate a diametric pair of circulation or discharge ports in the control device 10, the port 25 connecting the fluid supply or reservoir 27 of a filter unit 28 through a conduit 29 and by-pass connection 30. The port 26 is connected, through by-pass connection 31, with a conduit 32, the latter having therein a sight glass 33, a flow meter 34 of usual and well known construction, and a circulation heater 35.

In another pair of diametric ports 36 and 37 of control device 10, the port 36 is connected through a by-pass connection 36a with the discharge conduit 38 from a trap 39, which trap is connected in a conduit 40 having a sight glass 40a therein. Port 37 of said pair is connected with a second circulation heater 41 in a conduit 42, which conduit connects the filter unit 28 as at 43.

The outlet conduit 44 from heater 35 is preferably provided with a valve casing 45, having at least three ports for controlling the flow therethrough as hereinafter set forth, one of said ports being connected to conduit 44.

Another of the ports of the valve casing 45 is provided with a flexible service conduit 46 connecting with the inlet passage 47 of an adapter 49 which is applied to and secured in the usual drain opening 50 of a lubricant receptacle, such as an internal combustion engine crank case 51.

The adapter 49 preferably has a separate outlet passage 48 to which is connected a flexible service line or return conduit 52. 45a designates a valve casing having one of its ports connected with the conduit 40, and another port connecting the conduit 52.

Further referring to the port connections of the control device 10, a port 53 is connected by a conduit 54 with the conduit 32 at a point between the meter 34 and heater 35, and its diametrically disposed port 55 is connected through by-pass 36a with the conduit 38 and trap 39. 32a designates a check valve in conduit 32 between the meter 34 and the junction of conduits 32 and 54.

Additional pairs of ports in the control device 10 are provided, as for example, at 56—57, the port 56 connecting with a conduit 58, including a suitable flexible portion 59, for use in connection with an additional oil supply or drum 60. Port 57 connects through by-pass connection 31 and meter 34 with the conduit 32.

Also, a conduit 61 having flexible portion 62 connects the device 10 by a port 63, the latter having its diametric port 64 connected with conduit 29 through by-pass connection 30, said line 61—62 being also adapted for use in conjunction with said additional oil supply 60, as will hereinafter appear.

In the operation of my invention, as for example in cleansing or flushing the engine of an automobile or the like, the used lubricating oil is drained from the crank case 51 in the usual manner by removing the drain plug from opening 50.

The adapter 49 is then secured in said opening as by screw threads or other suitable means, whereby to connect the interior of the crank case with the conduits 46 and 52. While separate entrance may be made to the crank case by the insertion of each conduit, I prefer to more conveniently provide for delivery and withdrawal of fluid through the single adapter having the aforesaid separate branch passages 47 and 48 communicating with conduits 46 and 52 respectively.

With a supply of flushing liquid or oil in the reservoir 27, the pump 11 is placed in motion as by a suitable driving motor indicated at 67. The handle 23 of the control device 10 is placed in position #1, thus placing ports 25 and 26 in communication with the pump to draw oil from the reservoir 27, through conduits 29 and 30 into the control device through port 25, through the pump back to the control device and into conduit 32 through port 26 and by-pass 31. In this position ports 64 and 57 are closed by the control device.

The flushing oil is thereby passed through sight glass 33 where its clean condition may be observed, through meter 34 to measure the quantity supplied to the crank case, and through the heater 35 to conduit 44. The valve of casing 45 is placed in position to deliver said oil to conduit 46 whereby it enters the crank case through adapter 49.

When the desired quantity of oil has been delivered to the crank case 51, as indicated by the meter 34, the member 14 of control device 10 is rotated to position #3, thereby placing conduits 46 and 52 in circulation through port 53, conduit 54, heater 35 and pipe 44 in communication with the pump and crank case for recirculating flow of oil, the return flow taking place by way of conduit 52, valve casing 45a, conduit 40, sight glass 40a, trap 39, conduit 38, by-pass 36a and port 55. The oil thus returning from the crank case is then passed through pump and control device, and from the latter by port 53 through conduits 54 and 32, heater 35, and conduits 44 and 46, to adapter 49 and returned into the crank case. During such circulating flow, check valve 32a prevents the back flow of the dirty oil to meter 34.

Such continuous recirculation through the crank case is maintained for a sufficient period of time to remove by means of the trap 39, the sludge, metal particles and other foreign matter from the crank case, the flushing oil being maintained at a suitable temperature by the heater 35. The trap 39 may be of any suitable construction, as for example, employing a plurality of screening baffles as illustrated, and a sump for collection of the foreign matter removed from the oil. It will be noted that the trap functions in advance of the control device and pump, whereby injurious metal particles and the like are removed so as to prevent the passage thereof through the said device and pump.

By the continuous heating and recirculating introduction and removal of the flushing oil at the lowermost portion of the crank case, I am enabled to remove the foreign particles such as metal pieces, etc., which normally settle to the

bottom, and are not removed by the usual manner of draining the crank case.

While the adapter 49 may be employed as shown, I prefer to employ the adapter construction as well as the fluid application and distribution within the lubricant receptacle, as shown and described in my application of even date, Serial No. 197,430, now Patent No. 2,240,227, issued April 29, 1941.

Attention is called to the fact that the foregoing initial flushing process is preferably utilized while the engine of the automobile or the like is still, whereby to better remove the foreign matter from the oil pump screen and inner parts of the engine, without the abrasive foreign particles being conveyed to the oil passages of the engine, or being sucked against and held by the pump screen.

Following the recirculation operation, the control device member 14 is rotated to position #4, whereby ports 36 and 37 are placed in communication with the pump 11, and the body of circulating oil is drawn from the crank case through conduits 52, 40, trap 39, conduit 38, and by-pass connection 36a to port 36, from whence the dirty oil passes by conduit 17 through the pump back to the control device 10 and out through port 37 by conduit 42 and heater 41 to the filter 28. The dirty oil passes upwardly through the filter to the reservoir 27 for re-use.

In order to clean the oiling system throughout the motor, the foregoing operations are preferably followed by supplying a fresh charge of clean oil to the crank case by rotating member 14 of the control device to position #1 as before. When the required quantity is delivered, the cleaner apparatus is stopped, and the automobile engine is run to distribute the flushing oil therethrough, following which the recirculation cycle may again be utilized for trapping removal of the foreign matter. These operations may be continued until the flushing oil returns clean, indicating that the engine is entirely clean.

In the event it is desired to cleanse the crank case of a large Diesel engine or the like, it is necessary to provide for the supply and refining or reclaiming of additional quantities of flushing oil. By means of my invention, I am enabled to draw upon an additional separate supply of oil for this purpose, to refine or reclaim such oil during the operation of the apparatus, and to return such additional oil to its separate container.

For this purpose, member 14 of the control device 10 is rotated to position #2, whereby, through aligned ports 56 and 57, flushing oil is drawn from container 60 through conduits 59 and 58, through the device 10 and pump 11, and is delivered through port 57 and by-pass 31 to meter 34, conduit 32, heater 35, conduits 44, valve casing 45 and conduit 46, and to the crank case 51 through inlet 47 of adapter 49. Such additional oil may of course be recirculated as hereinbefore described in connection with position #3 of the control device.

To refine or reclaim the added oil when the flushing operation is completed, member 14 of the control device 10 is rotated to position #4, whereupon the oil is returned through the filter 28 to reservoir 27 as before.

When the reservoir 27 is substantially filled, the control device is adjusted to position #5, thereby establishing pump circulation through ports 63 and 64 to draw the oil from the filter 75

reservoir through conduit 29 and by-pass 30 to port 64, through device 10, conduits 17 and 16 and pump 11, for discharge from port 63 through conduit 62 to the container 60. The filtration and returning steps of position #4 and #5 may then be repeated until the volume of added oil has been filtered and returned to the container 60.

Should more oil be inadvertently returned to container 60 than is desired, upon adjusting the control device to position #6, the conditions of position #5 become reversed, and the pump 11 provides a flow in the reverse direction to that described for position #5, whereby oil is delivered from the container 60 to the reservoir 27 as will be readily understood. This circulation of position #6 is likewise utilized for initially charging the apparatus reservoir with a supply of flushing oil.

When cleansing or flushing automobile crank cases, it is desirable to also clean the transmission and differential cases. This may be readily accomplished by my invention through the use of an additional delivery conduit 65 connected with a port of the valve casing 45 and with a second valve casing 66. By means of said valves the heated flushing oil supplied by operation #1 of the apparatus may be diverted to said conduit, and by conduit 67 and separate flexible conduits 68-69, the oil is separately forced into the transmission and differential cases 70 and 71 respectively. Suitable valves 72 are provided in conduits 68 and 69 for separately controlling the same.

The oil so supplied to the cases 70 and 71 may be retained therein by valve of casing 45 until the crank case cleaning is completed. For the return thereof, a conduit 73 connects valve 66 and valve 45a of the conduit 52, and upon proper adjustment of said valves, the dirty oil may be drawn from the cases by operation #4, through trap 39 and back to filter 28. Additional separate supply and return operations may however be employed to complete the cleansing of the said cases 70 and 71.

In the described cleansing or flushing operations, the use of heated flushing oil materially increases the efficiency of the process, both in removing the sludge and foreign material, and in filtering or reclaiming the used flushing oil. My invention contemplates heating the oil during its circulation, and in relation to the control of the apparatus.

Figs. 5, 6, and 7 illustrate a preferred form of circulation heater, it being understood that my invention is not to be limited thereto, as other heaters capable of heating the flushing oil during the flow thereof may be employed. As illustrated, the heater comprises a pair of parallel elongated looped tubular electric heating elements 78 and 79 containing the usual spiral resistor elements as indicated in the broken-away portions in Fig. 5. Loops 78 and 79 are disposed one inside the loop of the other as shown, and are secured to a common header or base 80 in fluid-tight connection. Suitable connections are made through said header from the elements to external binding posts 81 for electrically connecting said elements as hereinafter described.

The elements are enclosed in a jacket 82, preferably having the irregular shape as shown in Fig. 7, whereby a substantially uniform transverse flow area is maintained around the legs of the heating elements, the said area being sufficiently restricted, and together with the longi-

tudinal dimension of the heater, determining the proper heating of the oil passed therethrough.

At the lower or entrance end, the jacket is secured to the header 80, and at the upper end tapers into connection with its outlet conduit connection 83. 84 designates a lateral inlet connection at the lower portion of the jacket.

It will be noted that the heater 35 is located to receive the oil passed through and therefore measured by the meter 34.

Likewise the heater 41 is located in relation to the circulation so as to only receive the quantity of oil which has been so metered. In other words, the heating system of my invention only acts upon the required volume of oil being utilized, and no more.

To further the efficiency and economy attained by such heating system, I prefer to energize the electric heaters in accordance with the flow of fluid therethrough, which aim may be accomplished by actuation of the heater control by or through the control device 10, as for example, as indicated in Fig. 8.

Thus, the stem or shaft 15 of the control device 10 is provided with a ring contact 85 insulated from and rotatable with said shaft, said contact being energized by a brush 86 from one side 87 of a source of electrical power E. A radial contactor arm 88 extends from the ring 85 for contact with an arcuate series of independent contacts 1a, 2a, 3a and 4a, said series of contacts being spaced in radial alinement with the respective positions #1, #2, #3 and #4 of the control device 10.

Contacts 1a, 2a and 3a are connected by a wire 89 with the other side 90 of the source of power E, said wire 89 also connecting element 78 of heater 35 in series therewith. Similarly, contact 4a is connected in series with element 78 of heater 41 and line 90 by a wire 92.

In operation, when the control device is in position #1, the circuit through contact 1a will be made, to energize the heater 35, whereby the oil passing therethrough from meter 34 will become heated for delivery to the crank case or other lubricant receptacle. In position #2, a circuit through contact 2a and heater 35 will be made to heat the additional oil being introduced, as from container 60, which oil is likewise metered.

Similarly, during the recirculation cycle of position #3, the circuit through contact 3a and heater 35 will be made to continue to heat the quantity of oil previously supplied. And further, upon returning any or all of such oil to the filter 28 in operation #4, the circuit is separately made through contact 4a and heater 41.

93 designates one wire connection and 94 the other, whereby the elements 78 of each of heaters 35 and 41 may be placed in parallel, through manual switches 95, with the elements 78 of their respective heaters, whereby additional heating may be provided if necessary.

It is therefore seen that the electrical heating employed is energized in relation to the flow of flushing oil, and is operable only during the flow through the respective heaters, thereby providing the exact heating desired both as to its point of application as well as the duration thereof.

The filter unit 28 may be of any suitable construction. I prefer to employ, however, a double filter of the character illustrated, including an outer filter 96 and an inner filter 97, each consisting of a plurality of layers of fuller's earth or the like, and layers of mineral wool or the like, as indicated. In between the layers are provided

perforate plates and layers of material, such as burlap. Traps 98 are provided at the lower entrance end of the inner filter and also at the upper end thereof, the latter being in communication with a trap 99 at the lower portion of the outer filter through a perforate conduit 100.

For proper suction feed from the reservoir 27, and to insure priming of the pump 11, the conduit 29 connects with a flexible conduit 29a which 10 has the open end thereof supported by a float 101. Such means also tend to prevent the delivery of sediment which may be present in the bottom of the reservoir. 102 indicates an air vent for the reservoir 27.

15 Fig. 2 illustrates a simplified form of the invention which may be employed for types of flushing service requiring an apparatus of lesser capacity. Such a machine may be manufactured and sold at a lower price and yet may be operated to cleanse or flush crank cases and the like with the same high efficiency of the larger and more expensive machine.

The control device or valve 10a has a lesser number of pairs of ports and adjustment positions. In position #1, oil is drawn from the reservoir 27a of filter unit 28a through a conduit 29b, through the control device and pump 11a, and is delivered from the control device through meter 34a and heater 35a in conduit 32b to flexible conduit 46a, and to the crank case 51 through adapter 49a.

Position #2 of the control device connects the latter and the pump in circulation with the crank case, whereby the supplied oil is drawn 35 therefrom through flexible conduit 52a from adapter 49a, through conduit 40b, trap 39a, conduit 38a, and by-pass connection 36b, and delivered from the control device through conduit 54a to conduit 32b. The flow preferably enters

40 the latter conduit at a point between the meter 34a and heater 35a in advance of a check valve 32c preventing a back-flow through the said meter, and providing for flow through the heater and conduit 46a to the crank case.

45 In this manner the desired re-circulation of the flushing oil is provided with accompanying heating by the single heater 35a, the said heater being preferably energized in connection with the movement of the control device 10a as hereinbefore set forth. The foreign matter in the crank case is removed and collected by trap 39a as before.

50 In position #3 of the control device, the dirty oil is returned through conduits 52a and 40b, trap 39a, conduit 38a and by-pass connection 36b to the pump and control device, and is delivered from the latter through a conduit 42a to the filter unit 28a for refining as before. The filter unit 28a is preferably of the same general character as hereinbefore described.

55 My invention provides an apparatus for cleansing lubricant receptacles having a positive circulating flow at all times which produces a highly efficient cleansing or flushing treatment with accompanying economy of operation.

60 What I claim is:

1. In an apparatus for cleaning lubricant receptacles and the like, the combination with a fluid supply, of a conduit adapted to be connected 70 with the lubricant receptacle to be cleaned, a heater in said conduit, a pump, a central unitary control device including means for connecting the fluid supply and conduit with the pump for delivering fluid to the receptacle and including

means for operating the heater in relation to said fluid delivery.

2. In an apparatus for cleaning lubricant receptacles and the like, the combination with a fluid supply, of a conduit adapted to be connected with the lubricant receptacle to be cleaned, a pump, means in the conduit for measuring the quantity of fluid delivered therethrough, a heater in said conduit, and a central control device including means connecting the fluid supply and conduit with the pump for delivering fluid through the measuring means and heater to the receptacle and including means for actuating the heater simultaneously with the fluid delivery through said measuring means.

3. In an apparatus for cleaning lubricant receptacles and the like, the combination with a fluid supply, of a conduit adapted to be connected with the lubricant receptacle to be cleaned, a pump, a circulation controlling valve between the fluid supply and said conduit for connecting the fluid supply and conduit with the pump for delivering fluid to the receptacle, means in the conduit for measuring the quantity of fluid delivered therethrough, a heater in said conduit, and means actuated by and connected with the circulation controlling valve for operating the heater only during the flow of fluid through the latter.

4. In an apparatus for cleaning lubricant receptacles and the like, the combination with a fluid reservoir and a filter, of a pump, an adjustable control valve for selectively connecting the fluid reservoir and a lubricant receptacle with the pump for delivering fluid to said receptacle, and for connecting the lubricant receptacle and filter with the pump for returning the fluid from the receptacle to the filter, means in such circulation for measuring the quantity of fluid delivered to the receptacle, a heater between the measuring means and receptacle operable to heat the fluid during the flow thereof from the measuring means to said receptacle, and thermal controlling means for the heater in operative connection with the adjustable control valve.

5. In an apparatus for cleaning lubricant receptacles and the like, the combination with a fluid reservoir and a filter, of a pump, an adjustable control valve for selectively connecting the fluid reservoir and a lubricant receptacle with the pump for delivering fluid to said receptacle, and for connecting the lubricant receptacle and filter with the pump for returning the fluid from the receptacle to the filter, means in such circulation for measuring the quantity of fluid delivered to the receptacle, a heater operable to heat the fluid during the flow thereof to said receptacle, a second heater operable to heat the fluid during the flow thereof from the receptacle to the filter, and thermal controlling means for said heaters in operative connection with the adjustable control valve.

6. In an apparatus for cleaning lubricant receptacles and the like, the combination with a fluid reservoir and a filter, of a pump, a pair of conduits adapted to be connected with the lubricant receptacle to be cleaned, a single adjustable control device for selectively connecting the fluid reservoir and one of the conduits with the pump for delivering fluid to the receptacle, and for separately connecting the filter with one of said conduits for returning the fluid from the receptacle to the filter, a heater operable by and with the control device to heat the fluid during the flow thereof to the receptacle only, said control

device also being adjustable for selectively connecting the pair of conduits with the pump for recirculating the delivered fluid in the receptacle prior to the return thereof from the receptacle to the filter.

7. In an apparatus for cleaning lubricant receptacles and the like, the combination with a fluid reservoir and a filter, of a pump, a pair of conduits adapted to be connected with the lubricant receptacle to be cleaned, a single adjustable control device for selectively connecting the fluid reservoir and one of the conduits with the pump for delivering fluid to the receptacle, and for separately connecting the filter with one of said conduits for returning the fluid from the receptacle to the filter, means in such circulation for measuring the quantity of fluid delivered to the receptacle, a heater and thermal generating means therefor operable by and with the control valve to heat the fluid during the flow thereof to the receptacle, said control device also being adjustable for selectively connecting the pair of conduits with the pump for recirculating the delivered fluid in the receptacle prior to the return thereof from the receptacle to the filter.

8. In an apparatus for cleaning lubricant receptacles and the like, the combination with a fluid reservoir and a filter, of a pump, a pair of conduits adapted to be connected with the lubricant receptacle to be cleaned, a central unitary adjustable control device for selectively connecting the fluid reservoir and one of the conduits with the pump for delivering fluid to the receptacle, and for separately connecting the filter with one of said conduits for returning the fluid from the receptacle to the filter, means in such circulation for measuring the quantity of fluid delivered to the receptacle, said control device also being adjustable for selectively connecting the pair of conduits with the pump for recirculating the delivered fluid in the receptacle prior to the return thereof from the receptacle to the filter, means for generating heat for heating the measured fluid upon the initial delivery thereof to the receptacle and during the recirculation thereof, and controlling means for such generation consisting of a circuit regulating device in operative connection with the control valve.

9. In an apparatus for cleaning lubricant receptacles and the like, the combination with a fluid reservoir and a filter, of a pump, a pair of conduits adapted to be connected with the lubricant receptacle to be cleaned, a single adjustable control device for selectively connecting the fluid reservoir and one of the conduits with the pump for delivering fluid to the receptacle, and for separately connecting the filter with one of said conduits for returning the fluid from the receptacle to the filter, means in such circulation for measuring the quantity of fluid delivered to the receptacle, a heater operable to heat the fluid during the flow thereof to the receptacle, said control device also being adjustable for selectively connecting the pair of conduits with the pump for recirculating the delivered fluid in the receptacle prior to the return thereof from the receptacle to the filter, and means preventing the back flow of fluid through the measuring means during such recirculation while providing for flow through the heater and conduit to the lubricant receptacle.

10. In an apparatus for cleaning lubricant receptacles and the like, the combination with a fluid reservoir and a filter, of a pump, a single adjustable control valve for selectively connect-

ing the fluid reservoir and a lubricant receptacle with the pump for delivering fluid to the receptacle and for separately connecting the lubricant receptacle and filter with the pump for returning the fluid from the receptacle to the filter, a trap through which said returning fluid passes before reaching the control valve and pump, means for measuring the quantity of fluid delivered to the receptacle, a heater operable to heat the fluid during the flow thereof to said receptacle, and heat supply means therefor operatively connected with the control valve.

11. In an apparatus for cleaning lubricant receptacles and the like, the combination with a fluid reservoir and a filter, of a pump, a pair of conduits adapted to be connected with the lubricant receptacle to be cleaned, an adjustable control valve for selectively connecting the fluid reservoir and one of the conduits with the pump for delivering fluid to the receptacle, and for separately connecting the filter with one of said conduits for returning the fluid from the receptacle to the filter, said control valve also being adjustable for selectively connecting the pair of conduits with the pump for recirculating the delivered fluid in the receptacle prior to the return thereof from the receptacle to the filter, a trap through which the fluid passes before reaching the control device and pump during the return flow to the filter and during the said recirculation of the fluid, and means for heating the fluid upon the initial delivery thereof to the receptacle and during the recirculation thereof, said heating means being dependent on operation of the control valve.

12. In an apparatus for cleaning lubricant receptacles and the like, the combination with a fluid reservoir and a filter, of a pump, an adjustable control device for selectively connecting the fluid reservoir and the receptacle to be cleaned, and for separately connecting the receptacle and filter with the pump, whereby fluid may be delivered to the receptacle from the reservoir and returned therefrom to the filter, electrical heating means for each of the delivery and return circulations of fluid, and means connected with and actuated by the control device for energizing the heating means only during the flow of fluid therethrough.

13. In an apparatus for cleaning lubricant receptacles and the like, the combination with a fluid reservoir and a filter, of a pump, a conduit adapted to be connected with the lubricant receptacle to be cleaned, adjustable control means for selectively connecting the fluid reservoir and said conduit with the pump for delivering fluid to the receptacle, a conduit adapted to connect with an additional supply of fluid, said control means being adjustable to connect the last mentioned conduit with the pump and the first conduit for delivering additional fluid to the receptacle, means in said first conduit for meas-

uring the quantity of fluid delivered to the receptacle, and means dependent on operation of the adjustable control means for heating the fluid during the delivery thereof to the receptacle.

- 5 14. In an apparatus for cleaning lubricant receptacles and the like, the combination with a fluid reservoir and a filter, of a pump, a pair of conduits adapted to be connected with the lubricant receptacle to be cleaned, adjustable control means for selectively connecting the fluid reservoir and one of said conduits with the pump for delivering fluid to the receptacle, an intervening meter, a check valve preventing return flow through said one conduit, a conduit adapted to connect with an additional supply of fluid, said control means being adjustable to connect said last mentioned conduit with the pump and said delivery conduit for delivering additional fluid to the receptacle, the control means also being adjustable to connect the other of said pair of conduits with the pump and filter for returning the fluid from the receptacle to the filter and reservoir.
- 15 15. In an apparatus for cleaning lubricant receptacles and the like, the combination with a fluid reservoir and a filter, of a pump, a pair of conduits adapted to be connected with the lubricant receptacle to be cleaned, adjustable control means for selectively connecting the fluid reservoir and one of said conduits with the pump for delivering fluid to the receptacle, an intervening meter, a check valve preventing return flow through said one conduit, a second pair of conduits adapted to connect with an additional fluid supply, said control means being adjustable to connect one of said second pair of conduits with the pump and said delivery conduit for delivering additional fluid to the receptacle, the control means also being adjustable to connect the other of said first pair of conduits with the pump and filter for returning fluid from the receptacle to the filter and reservoir, and for separately connecting the other of said second pair of conduits with the reservoir and pump for delivering said returned fluid to the additional fluid supply.

- 50 16. Apparatus for alternately supplying solvent to, and removing solvent from, the crankcases of automobile engines or the like, comprising conduit means engageable with the crankcase to be cleaned, a clean-solvent supply reservoir, a return flow receiving chamber, means for conducting outgoing clean solvent from said reservoir into said conduit, including piping intermediate the two, a flow-meter operatively connected with said piping, and means for conducting returning dirt-laden solvent from said conduit into said receiving chamber, including piping by-passing said flow-meter.

GEORGE E. SAUSSURE.
